UNITED STATES PATENT OFFICE.

JOSEPH E. RALPH, OF NEWARK, NEW JERSEY.

CARD-INDEX.

No. 857,202.

Specification of Letters Patent.

Patented June 18, 1907.

Application filed February 1, 1906. Serial No. 299,051.

To all whom it may concern:

Be it known that I, JOSEPH E. RALPH, a citizen of the United States, residing at Newark, in the county of Essex and State of New Jersey, have invented certain new and useful Improvements in Card-Indexes; and I do hereby declare the following to be a full, clear, and exact description of the invention, such as will enable others skilled in the art to which it appertains to make and use the same.

This invention relates to card indexes, and has for an object to provide an index embodying new and improved features of convenience, rapidity, accuracy and reliability of selection of the several cards similarly sub-classed.

This invention is intended to recognize and operate in conjunction with the several card index systems in use at the present time, wherein divisions are made by notches or cuttings along the top of the cards, by colors, by printing and ruling and by the adding or attaching of indications or equivalents to the edges of the cards.

An object of this invention is to provide a card index wherein the classification characteristics on the cards are divided into two or more main groups, and each of the said groups sub-divided into a plurality of sub-classes, and with means for selecting from all of the cards those having the characteristics of any one subclass of either group, or of two sub-classes, one from each group, and with means whereby the cards selected from each group are positioned differently from any of the other cards contained in the said index, and those cards which belong to a subclass of each of the groups will occupy a position other and different from any of the cards in either of the groups which do not belong to two of said subclasses.

Another object of the invention is to provide a system which may be used in conjunction with the said systems, or other systems dependent entirely upon the keenness of the eye of the operator in noticing slight variations in shape, color, etc., by providing automatic means for elevating all the cards of a single desired sub-division of a particular classification so pronouncedly and markedly that there can be no mistake as to which cards are so particularly picked.

A further object of the invention is to provide means for selecting from the whole case or tray, the several cards of still another sub-

division of another distinct group by elevating the said cards to another and distinct position from that assumed by the sub-class previously selected and above the normal 60 position of the cards in the case, and embodying the resultant feature of distinctly elevating all of the cards that are members of the particular sub-divisions of the two separate groups to a position different from 65 that assumed by the cards of either of said groups or from the normal position of the cards in the tray.

With these and other objects in view, the invention comprises certain novel construction, combinations and arrangements of parts, as will be hereinafter fully described and claimed.

In the accompanying drawing:—Figure 1 is a view in front elevation of a conventional card arranged for operation in conjunction with means, in the case or tray containing the cards, for elevating cards as desired. Fig. 2 is a longitudinal, sectional view of a box, or tray containing cards and showing in side elevation one of the channel bars used to elevate the cards. Fig. 3 is a transverse sectional view of a box or tray showing in transverse section the channel bars and elevating means, one of said bars being shown as elevated and the others as depressed. Fig. 4 is a plan view of one of the members from which is made the device attached to the lower edges of the cards and by which they are elevated. Fig. 5 is a view in edge elevation of the member shown in and described for Fig. 4. Fig. 6 is a view in edge elevation of the elevating device completed with the washer between the two elements of said member. Fig. 7 is a diagrammatic view showing the position of a card raised to indicate its membership in a certain sub-class of a division. Fig. 8 is a diagrammatic view showing the position of a card raised to indicate its membership in a sub-class of another division, than shown in Fig. 7. Fig. 9 is a diagrammatic view showing the position a card would assume which happens to belong to both sub-classes of two distinct divisions, shown in Figs. 7 and 8, in relation to and in connection with cards, each of which belongs to the sub-class of but one division.

Like characters of reference designate corresponding parts throughout the several views.

In its preferred embodiment the card index forming the subject-matter of this appli-

cation comprises a container 10 in the form of a box, drawer, case, tray or other receptacle in the bottom of which are mounted a plurality of channel bars 11 upon each side.

5 The channel bars 11 are arranged to be raised vertically by means of links 12 and 13, connected by a pin, as 14, to form a toggle joint operated by the pull bar 15 extending outwardly through the front side or end of the

10 box and each terminating in a knob or marker of any approved form, as 16. The several channel bars 11 may be separated by division boards or plates 17 forming longitudinal grooves in which the said channel bars

15 are normally seated and from between which they may be raised by a pull upon the knob 16 to be elevated above the said division boards 17.

Within the container is contained a plurality of cards 18, disposed in a vertical position and transversely of the case or tray and having bearing members 19 resting upon the upper surface of the channel bars 11. The cards 18 may be of any approved size and

20 conformation, and preferably formed with a plurality of scallops or semi-circular indentations 20 arranged in groups upon each end of the lower edge of the card and with a section, as 21, between the said groups, which

25 section is not provided with perforations or cut in any manner. Above each of the said indentations 20 is provided an opening 22 which may be of any size and form, but preferably a small square hole as indicated. The bearing member 19 is composed of similar elements 23, each formed upon one end with a recess 24 and upon the opposite end with a tongue 25, which is bent or curved as at 26 to engage within the recess 24 of the co-acting

30 element, the said elements being reversely placed relative to each other, the curved tongue of each disposed within the recess of the other, one of said tongues being inserted through one of the openings 22, and a washer

35 27 being disposed between the said elements and within one of the scallops 20 and secured therein in any approved manner as by the rivet 28 inserted through the said elements and through the washer. Near the top edge

40 of the card is provided an indicator as 29 occupying any predetermined position and formed in any approved manner as by producing scallops or notches 30 along the portions of the card which are not to be used as

45 indicators, allowing the indicating section to remain standing at a normal height of the card, as indicated.

Indexes embodying this invention may be used for any purposes for which card indexes are used, and for convenience and clearness of description an index is here illustrated as for use in connection with a real estate business, and the card shown at Fig. 1 is arranged for and filled out conveniently for such use.

55 It will be noted that in Fig. 1 the several scal-

lops 20 along the lower left-hand end of the said card are designated as 1 Fam., 2 Fam., 3 Fam. 4 Fam., and factory, the abbreviation "Fam." intended to indicate family and the designations to indicate that the building 70 to be indexed upon the said card will be for one or more families, as indicated or a factory. As filled out, the card 18 is for a building occupied by three families and the bearing member 19 is engaged upon the said card in 75 the scallop 20 designated by 3 Fam. and the curved tongue 26 inserted through the opening 22 vertically above the said scallop. Upon the opposite end the said scallops 20 are indicated by iron, I and B, brick, B and 80 F, and frame, the abbreviation I standing for iron, B for brick and F for frame. As indicated upon the card the building indexed is a brick and the bearing member 19 is, therefore, secured in the scallop 20 indicated by "brick" 85 in the manner described for the securing of the similar member upon the opposite end of the card.

The indicator at the top of the card may indicate the value of the building as "5" 90 shown may be for the value of five thousand or arranged to indicate a value ranging from four to six thousand dollars. All of the cards having their bearing members 19 disposed similar to the position shown in Fig. 1, will 95 bear upon the channel member third from each side of the box or tray, and if it is desired to select from the several cards contained in the said tray all of the buildings occupied by three families, the knob 16 so designated is pulled to the position shown in Fig. 2, thereby elevating its associate channel bar 11, and with it the several cards having their bearing members resting thereon, which said cards will be elevated at the left-hand corner, as indicated in Fig. 7.

If it is desired to select from the several cards contained in the tray, all of the brick buildings, the knob 16 so indicated, is pulled to a similar position elevating thereby to the 100 position shown in Fig. 8, all of the several cards indexing brick buildings. Thus, those cards that are indexed brick buildings occupied by three families will be bodily and wholly raised to the position shown in Fig. 9 105 above the normal position of the cards in the box and to a position also wholly distinct from the position assumed by cards of but one of the sub-classes of either group that were acted upon by pulling actuating the two 110 knobs 16, as described. If it is desirable to select from among said groups, buildings valued at, say five thousand, the indicator upon the top edge of the card is brought into use and all of the cards so indicated may be 115 quickly selected from any or all of said sub-classes. It will be understood that the bearing member 19 will be differently secured to the said card for indicating a different number of families in a house or for a factory and 120

130

the bearing member indicating the construction of the building will be differently located if the building is of a construction other than brick. When the cards raised in any or all of 5 said sub-classes have been consulted they are lowered to normal position by pushing upon the knob 16 which lowers the channel bar 11 and the bearing members 19 acting thereon and therewith. It will be readily seen that 10 by pulling the knob 16, designated as 3, Fam. none of the cards indexed for other numbers of families will be manipulated or raised in any manner, but will remain at the normal position of the cards in the tray, the same being 15 true of the selection for construction, which selection may raise a sub-class of cards entirely distinct from those raised by the 3 Fam. knob or some of said cards may be indexed for both sub-classes whereupon both 20 ends of said card will be raised as above described, all other cards remaining at the normal position in the tray.

Having thus described my invention, what I claim and desire to secure by Letters Patent is:—

1. In a card index, means to raise the several cards of a plurality of groups of sub-classifications above their normal positions, and those classified under each such sub-classification, to a distinct position.
2. In a card index, a container, means to select and raise the several cards of a plurality of groups of sub-classifications above their normal positions, and those classified under each of said classifications to a distinct position.
3. In a card index, a container, a bar disposed within said container, cards of a particular groups of sub-classifications resting upon said bar, and means to raise the bar and the cards resting thereupon.
4. In a card index, a container, a plurality of bars disposed within said container, a plurality of cards within the container, and arranged with the cards of distinct sub-classifications resting upon different ones of said bars, and means to raise the bars and the cards resting thereon.
5. In a card index, a container, cards of a plurality of classifications within the container a channel bar disposed within said container, cards within said container and so arranged that cards of a distinct classification only rest upon the said channel bar, and means extending without the container for raising the channel bar and the cards resting thereon.

6. In a card index, a container, a channel bar disposed within and extending longitudinally of the said container, and with its 60 closed side uppermost, a card disposed within the said container and provided with a bearing member extending below the normal edge of said card and positioned to rest upon the said channel bar, and means extending 65 without the container to elevate the said channel bar and the said card.

7. In a card index, a card provided with bearing members secured upon its lower edge and adjustable longitudinally of the said 70 card.

8. In a card index, a card provided with spaced openings adjacent its lower edge, and bearing members secured in said openings and extending below the normal edge of said 75 card, and adjustable to any of said openings.

9. In a card index, a container, a plurality of bars disposed upon opposite sides and extending longitudinally of said container, cards within said container provided each 80 with depending bearing members arranged to be adjustably positioned for bearing upon either of said bars, and means to selectively elevate either of said bars and the cards resting thereon.

10. In a card index, a container, a plurality of bars disposed upon each side and extending longitudinally of the said container, cards within said container provided each with openings at each end along their lower 90 edges, depending bearing members arranged to be adjustably secured in either of said spaced openings, and means extending without the container to elevate either of said bars.

11. In a card index, a container, provided with a plurality of bars upon each side extending longitudinally thereof, cards within the container provided each with spaced scallops along the lower edge and grouped at each end 100 of said card and differently designated, bearing members arranged to be secured within either of said scallops and to extend below the normal edge of said cards and bear upon the upper surfaces of the corresponding bars, 105 and means extending without the container to elevate either of said bars.

In testimony whereof I affix my signature in presence of two witnesses.
